UNITED STATES PATENT OFFICE.

CHARLES A. DAHLEN, OF DULUTH, MINNESOTA, ASSIGNOR TO THE KLEARFLAX LINEN LOOMS, INC., OF DULUTH, MINNESOTA, A CORPORATION OF MINNESOTA.

TUFTING NEEDLE.

Application filed February 5, 1927. Serial No. 166,152.

This invention relates to tufting needles and has special reference to that type designed for hand use in the making of rugs or the like.

5 The principal object of the invention is to produce a more practical and efficient needle of this type.

Another object is to provide a more convenient and less tiresome form of such 10 needle for use by those constantly engaged in the art of tufting, as for example in a factory or the like.

Still another object is that of convenience in threading such a needle.

15 Further objects and advantages of the invention will appear in the following description thereof.

Referring now to the accompanying drawing, forming part of this application, and 20 wherein like reference characters indicate like parts:

Figure 1 is a horizontal sectional view partly in perspective, of one of the completely assembled needles embodying the invention; and

25 Figure 2 is an elevation of the threading wire for such needle.

1 represents an elongated, tapered, body portion or handle having a flared terminus 30 or head 2 at one end, the face of said head being convex as at 3. This handle or body portion is preferably formed of some very light material such as aluminum or the like, it being of sufficient size for convenient grasping in the palm of the hand.

35 A small axial hole 4 is formed the entire length of the handle, terminating in the head in an enlarged circular recess or chamber 5, the terminal of the bore 4 within the 40 head adjacent the recess being but slightly enlarged and internally screw threaded for the reception of the screw threaded shank 6 of the hollow needle 7.

The needle adjacent the shank 6 is 45 enlarged and squared, or at least formed rec-

tangular in shape as at 8 forming a hub for screw threaded manipulation of same in relation to the handle, and at 9 is shown a lock washer for securely holding the needle in the handle when properly attached thereto. The opposite end of the axial hole 4 is countersunk as at 10 to prevent undue wear or cutting of the yarn or thread being used.

At 11 is illustrated a fine wire, looped as at 12 at one end for insertion through the 55 handle and needle when combined, for conveniently threading same, such operation being obvious.

The recess 5 provides against clogging or wadding up of the material at the connection of the needle with the handle, as would occur if the needle was directly attached to the shank of the handle, and furthermore permits of ready adjustment of the length of the protruding portion of the needle, as 60 it is evident any thickness of washer or washers may be used about the shank of the needle and beneath the hub 8 thereof.

Having thus described the novel combination of handle and needle which comprises 70 the invention, what I claim and desire to secure by Letters Patent, is:

1. In combination, an elongated handle member having an enlarged head portion with a recess in the face thereof, and an 75 axial hole longitudinally of said handle, and a hollow needle adjustably mounted upon the bottom of the recess concentric with the bore of the handle, said recess forming an open chamber surrounding the 80 base of the needle.

2. The combination with a handle having an enlarged head, of a comparatively large and deep axial recess in the head thereof, a hollow needle screw threadedly mounted 85 axially of said recess, and means whereby said needle may be firmly secured therein at predetermined varying depths.

In testimony whereof I affix my signature.
CHARLES A. DAHLEN.
